WAGON OR TRAILER BODY WAGON BED

Lester B. Patrick, Mercury, Tex.

Application October 7, 1937, Serial No. 167,848

2 Claims. (Cl. 296—13)

This invention relates to a body or bed for use on a wagon, trailer or otherwise and it aims to provide a construction whereby the body is convertible into various forms and shapes so that a single wagon body may be advantageously used for various purposes in connection with which different shapes of bodies have been or are found advisable.

The more specific objects and advantages will become apparent from a consideration of the description following taken in connection with accompanying drawings illustrating an operative embodiment.

In said drawings—

15 Figure 1 is a side elevation of the body having supplemental side and end boards;

Figure 2 is an end elevation of the body of Figure 1;

20 Figure 3 is a vertical sectional view taken on the line 3—3 of Figure 1;

Figure 4 is a central longitudinal sectional view taken on the line 4—4 of Figure 2;

Figure 5 is a view similar to Figure 1 showing the use of second supplemental side boards;

25 Figure 6 is an end view of the form of Figure 5;

Figure 7 is a vertical sectional view taken on the line 7—7 of Figure 5;

Figure 8 is a transverse sectional view through a body employing parts to hold the supplemental 30 sides in extended horizontal position;

Figure 9 is an end elevation showing an end elevation with a supplemental body built-up on the form of Figure 8;

Figure 10 is a transverse sectional view through a body of the form of Figure 9; and

35 Figure 11 is a detail horizontal section taken on the line 11—11 of Figure 9.

Referring specifically to the drawings wherein like reference characters designate like or similar parts, my improvements are associated with a conventional or any wagon body consisting of a floor 10 side boards 11 and end boards 12, the side boards and bottom being secured together in any suitable manner and mounted on a wagon or other vehicle in any manner preferred and preferably having cross sills 12' and cleats 13 extending therefrom and fastened to the side boards 11. The end boards 12 are preferably vertically slidable for application and removal, being held in place by guides 14. Removable bolts or rods 15 preferably extend through the side boards 11 and across the end boards 12, the same being detachable and having a single nut 16 screwed thereon.

55 In carrying out the invention, supplemental

side boards are provided at 17 in connection with supplemental end boards 18. The supplemental side boards 17 have hinge hook members 19 suitably fastened thereto at 20 which are detachably engaged in eyelets 21 of bars 22 fastened at 23 to the side boards 11. Such structure pivotally mounts the hooks proper 24, of the hinge hook members 19 in the eyelets 21 and also pivots them in the eyelets 21. A cotter key 25 may be passed through an opening in one of the hook members 24 to prevent accidental detachment of the supplemental side boards 17.

The last mentioned side boards have spaced guides at 26, like those at 14, between which the end boards 18 are removably slidable. Rods or 15 bolts 27, like those at 15, are adapted to be passed through the supplemental side boards 17, being removably held in place by nuts 28 thereon.

Second supplemental side boards are provided at 29 in cooperation with second end boards 30. Said second supplemental side boards 29 are provided with stakes 31 which extend below the lower edges of the side boards 29. The latter are adapted to removably rest on the upper edges of the supplemental side boards 17 and the stakes 25 31 detachably slide into pockets or brackets 32 fastened to the supplemental side boards 17.

Said end boards 30 are vertically removable and detachable, being slidable between guides 33 on the supplemental side boards 29. Long hook 30 members 40 are pivoted at 41 to one of the supplemental side boards 29 and are detachably engageable in eyelets 42 of elongated rods 43, pivoted at 44 to the companion supplemental side board 29.

As shown in Figure 8, all of the supplemental side and end boards may be discarded with the exception of the side boards 17. Such side boards 17, as shown in Figure 8 may be moved into horizontal positions outwardly of the wagon body, being swung to such positions on the hooks and eyelets 24 and 21. It will be noted that the construction of said hooks and eyelets is such as to provide a space, in the condition of Figure 8, between the upper edges of the side boards 11 and the adjacent portions of the side boards 17 so that bars 45 may be removably passed through such spaces, resting on the upper edges of the side boards 11 and supporting the supplemental side boards 17.

Any desired number of the said bars 45 may be employed, for instance four and at each end of each of them, a pocket or bracket 46 is provided. In view of this fact, the body may be built-up into the form of Figures 9, 10 and 11 by disposing the 55

supplemental side boards 29 on the side boards 17 at a right angle with the stakes 31 removably extending through the pockets or brackets 36.

In the latter form, modified supplemental end boards 48 are used, the same being detachable, and having irregular lower edges so as to fit and rest on the supplemental side boards 17 and the upper edges of the side boards 11. The aforesaid hooks 40 and rods 43, in the present relation 10 may engage hooks 49 suitably arranged on the end boards 48.

Various changes may be resorted to provided they fall within the spirit and scope of the invention.

15 I claim as my invention:

1. A body of the class described having main side walls, supplemental side walls selectively disposable vertically and horizontally, means at the top of the main side walls pivotally connecting the main side walls and the adjacent supplemental side walls together, means to hold the supplemental side walls against displacement in their vertical position, pockets on the supplemental side walls, second supplemental side walls, said

second supplemental side walls having stakes detachably engageable in said pockets to secure the second mentioned side walls above the first mentioned supplemental side walls, bar means disposable on the main side walls and passable through said pockets to support the first mentioned side walls in horizontal position, said bar means having pockets at the ends thereof to receive the said stakes in the horizontal position of the first mentioned supplemental side walls. 10

2. A body of the class described having side walls, supplemental side walls hinged thereto so as to assume horizontal positions outwardly thereof when raised above their upper edges, said supplemental side walls also being disposable vertically, pockets on the supplemental side walls for engagement by stakes to support additional walls above the same, and bar members removably disposed transversely of the supplemental side walls between the same and said edges to support the supplemental side walls in horizontal position, said bar members extending through said pockets. 15 20
